UNITED STATES PATENT OFFICE.

JOHN ROBERTS BOLTON, OF NEW YORK, N. Y., ASSIGNOR TO A. G. SPALDING & BROS., OF JERSEY CITY, NEW JERSEY, A CORPORATION OF NEW JERSEY.

GOLF PRACTICE-NET.

No. 920,907.

Specification of Letters Patent.

Patented May 11, 1909.

Application filed November 6, 1908. Serial No. 461,261.

To all whom it may concern:

Be it known that I, JOHN ROBERTS BOLTON, a British subject, residing in the borough of Brooklyn, of the city of New York, in the State of New York, have invented 5 certain new and useful Improvements in Golf Practice-Nets, of which the following is a specification, reference being had to the accompanying drawings, forming a part hereof.

The object of this invention is to provide a device with which the golf player, whether tyro or expert, may practice at home, outdoors or indoors, without going upon the 15 links.

Practice is sometimes undertaken with a ball fastened at the end of a cord, but this device is of little practical value, partly because of the frequent breakage of any cord 20 which is sufficiently light, and partly because of the fact that accuracy of flight of the ball is destroyed by the cord, however light, so that inaccuracy is developed in the player rather than accuracy. Moreover the 25 ball generally lands at the limit of the cord away from the player and must be recovered after each stroke, while the length of flight permitted by the cord necessarily precludes the use of the device indoors. The 30 device in which this invention resides, however, not only permits practically every form of stroke to be practiced, even in close quarters, but it effects the return of the ball immediately to the feet of the player or 35 within his easy reach.

The device comprises a net to receive the ball, and a support therefor which is so constructed as to be capable of being folded into small compass so that the device can be 40 transported readily and set up quickly in any convenient place, the net being inclined toward the feet of the player and practically to the position of the player.

The invention will be more fully explained hereinafter with reference to the accompanying drawing in which—

Figure 1 is a perspective view of the practice net, with what may be called the lid shown by full lines in its lower position and 50 by dotted lines in its lifted position, and Fig. 2 is a view thereof in front elevation.

The supporting frame for convenience, cheapness, lightness and ease in folding and setting up comprises a saw-buck frame, consisting of a double set of crossed members

a, a', the members of each set being pivoted upon one another, as at *b*. Corresponding members are united and braced near their lower ends by detachable rods *c, c* and the upper rear ends are braced and united by a 60 detachable rod *d*. Also pivoted upon the upper rear ends of the members *a'* are extension rods *c, c*, to the outer ends of which may be secured a rod or cord *f*. The various members of this frame are preferably 65 made of comparatively light but strong wooden rods. As thus constructed the frame can be folded up readily by detachment of the several detachable rods, so that all of the members may be placed parallel 70 and assembled in a compact bundle. It is also readily set up whenever and wherever desired and stands firmly upon the lawn or 75 floor or court or room.

The net *g*, of suitable mesh, like a tennis 75 net, for example, is so supported that its upper end is at about the height of the shoulders of a player of ordinary height, while its lower edge is drawn forward toward the position in which the player stands, its corners being preferably secured to the floor or other surface upon which the net is erected, as at *h*, by any convenient means, such as a weight or pin or hook. The main portion of the net hangs in a 80 gently inclined plane, while the edge portion *i*, away from the player, is turned up to form a guard for the purpose of preventing the movement of the balls beyond the edge of the net and out of reach of the 85 player.

In its application to the supporting frame shown, the upper edge of the net is attached to the cross rod or cord *f* and somewhat below its upper edge the net is attached to the cross rod or guard *d*, while its 90 lower edge or end is drawn out toward the feet of the player and secured as at *h*. If the player be a right hand player, the right hand edge portion of the net, as the player faces it, is drawn up to form a guard and 95 may be supported on the upper portion of the right hand leg *a*. If the player be a left hand player, the left hand edge portion of the net is similarly drawn up to form a guard. The upper or lid portion or flap *g'* of the net may either be turned down into a horizontal position, with the extension rods *e, e*, supported upon the upper ends of the legs *a*, for certain kinds of practice 105 shots, or it may be turned into an upright 110

or nearly upright position, as shown by dotted lines in Fig. 1, in which it is supported by the tension of the net for other classes of shots. The main portion of the net is provided with a series of pockets k , k' , k^2 , in line.

The use of the net for practicing various kinds of shots or strokes will be readily understood by those skilled in the art. For 10 driving, iron shots, &c. the net is generally used with the lid or flap g' turned down to a horizontal position, to stop the ball as it is deflected upward after striking the main portion of the net. For full mashie shots, 15 the lid or flap is raised to its full height. For the practice of pitching shots, the pockets k , k' , k^2 come in play, giving accuracy in direction as well as exactness in height. Should the ball lodge in one of the 20 pockets it is easily removed by the hand of the player, but otherwise, after a shot of any kind, the ball is returned at once to the feet of the player, so that a succession of shots can be made with great rapidity. It 25 will be seen that as the ball cannot escape the net, if even the most ordinary skill be exercised, the device can be used wherever there is room to swing a club, whether upon the lawn or in a paved court or in a room.

30 It can be readily set up and readily taken

down and can be packed in a small compass either for carrying from place to place or for storing.

I claim as my invention:

1. The combination with a supporting 35 frame, comprising a double set of pivoted crossed members, detachable rods uniting and bracing corresponding crossed members and extension rods pivoted upon the upper rear ends of the crossed members, and a net 40 having its upper portion supported by said frame and having its lower end free and adapted to be carried forward toward the feet of the player.

2. The combination with a supporting 45 frame, comprising a double set of pivoted crossed members, detachable rods uniting and bracing corresponding crossed members and extension rods pivoted upon the upper rear ends of the crossed members, and a net 50 having its lower end free and adapted to be carried forward toward the feet of the player, the body of the net being provided with pockets.

This specification signed and witnessed 55 this 4th day of November A. D., 1908.

JOHN ROBERTS BOLTON.
